CONCRETE PLACEMENT APPARATUS

Corwill Jackson, Ludington, Mich.

Application January 6, 1940, Serial No. 312,739

9 Claims. (CL. 94—48)

This invention relates to improvements in concrete placement apparatus.

The main objects of this invention are:

First, to provide a machine or apparatus for the placement of concrete such as pavements, concrete slabs, the walls of ditches, conduits, or the like.

Second, to provide a machine or apparatus which is capable of a wide range of adjustment to meet particular conditions such as engineering specifications, formula of material placed, and the like.

Objects relating to details and economies of the invention will appear from the description to follow. The invention is defined in the claims.

Preferred embodiments of the invention are illustrated in the accompanying drawings, in which:

Fig. 1 is a vertical longitudinal section of a machine or apparatus embodying the features of my invention on line 1—1 of Fig. 2, certain of the parts being conventionalized for convenience in illustration.

Fig. 2 is a fragmentary front elevation.

Fig. 3 is a fragmentary plan view.

Fig. 4 is a fragmentary section showing a modified form or embodiment particularly in the mounting of the vibrating rotor.

In the embodiment of my invention illustrated in the accompanying drawings, the reference numeral 1 indicates the main carriage of a paving machine provided with carrying wheels 2 adapted to travel on the longitudinal form members 3. The paving machine 1 is provided with a reciprocating screed designated generally by the numeral 4 and comprises a shoe 5 and a face plate 6, the face plate being adapted to support a substantial amount of material to be treated.

The screed is reciprocated by suitable means including the crank 7 and pitmans 8. The screed is advanced with the carriage, thrust sustaining rollers 9 being provided. The screed is provided with forwardly and outwardly converging wings 10 which overhang the side forms 3.

I provide an auxiliary vibratory element carrying frame which in this embodiment comprises the end or side members 11 which are adjustably secured by means of clamps 12 and 13 to the push bars 14 which are pivotally mounted on the main carriage at 15. The end members 11 are connected by the tubular transverse frame member 16. This auxiliary carriage is provided with wheels 17 which are carried by wheel supporting brackets 18 pivoted at 19 on the frame side members 11 and operatively connected to a hydraulic

motor designated generally by the numeral 20 by means of the link 21. I have illustrated only one end of this carrying frame. It will be understood that the other is a substantial duplicate thereof, the hydraulic motor 20 being connected to a link corresponding to the link 21 at the other side of the machine by means of the rockshaft 22 which is arranged within the tubular frame member 16. This rockshaft is connected to the motor 20 by means of the arm 23, a corresponding arm at the other end of the rockshaft being connected to a link corresponding to the link 21.

An adjustable stop 24 is provided to limit the clockwise swing of the wheel carriers 18 about pivot 19 and thus determine the lowered position of the vibratory member. This stop, however, is capable of a wide range of adjustment.

Bolted to the top of bar 14 is an automatic cut-off switch 161 actuatable through a tappet 162 engaged by an abutment on rock shaft 22 when the shoe is elevated by the fluid matter to inoperative position, whereby to prevent destructive or undue shaking thereof by the vibrator when the shoe is out of engagement with the work.

The vibratory member designated generally by the numeral 25 comprises a horizontal shoe 26 of substantial width. This shoe is provided with a face plate 27 of such height as to rearwardly sustain for advancement a substantial amount of material to be treated as is illustrated in Fig. 1.

A plurality of spaced vertical plate-like vibratory members 28 are secured to the face plate to project substantially forward therefrom and these have narrowed portions 29 extending transversely below the shoe. These plates 28 are arranged in spaced parallel relation and constitute auxiliary vibratory members and provide a plurality of pockets 30 at the front of the face plate adapted to receive and advance material being treated, the members 28 coating with the face plate to effectively vibrate this material and to transmit vibrations beyond the confines of the pockets a substantial distance into the material. These plates have enlargements 32 of rounded section on their outer edges, these enlargements serving the purpose of reinforcing the plates and also presenting an enlarged surface to receive wear and to transmit vibrations.

The vibratory element is provided with a top plate 33 which serves as an effective housing for the vibrating unit 34 which in this case is an electric motor, the rotor 35 of which is provided with an unbalancing weight 36.

In the embodiment of Fig. 1, the axis of the

rotor is disposed longitudinally of the vibratory element, the motor being mounted on suitable brackets 37 rigidly secured to the shoe and face plate of the vibratory element.

In the embodiment shown in Fig. 4, the axis of the rotor is disposed transversely of the vibratory element. The vibratory element in both embodiments is supported from the auxiliary frame by the flexible non-extensible hangers 38 which permit free vibratory movement thereof and is also provided with a flexible non-extensible draft member 39. By thus mounting the vibratory element it may be vertically adjusted relative to the material and relative to the screed 4 and also adjusted to and from the screed, this latter adjustment being effected by adjusting the clamps 12 and 13 on the push bars 14. It is preferred, however, that the heel of the vibratory member be spaced from the screed so that the material treated by the vibratory element may flow upwardly in front of the screed as indicated at 40.

I have illustrated and described my machine or apparatus for the placement of concrete in a very practical embodiment thereof. I have not attempted to illustrate or describe other embodiments or adaptations as it is believed that this disclosure will enable those skilled in the art to embody or adapt the same as may be desired.

Having thus described my invention, what I claim as new and desire to secure by Letters Patent, is:

1. In a machine of the class described, the combination with a main carriage, of a reciprocating screed advanced with said main carriage, a vibratory element comprising an elongated flat shoe of substantial width disposed in advance of and in parallel relation to said screed and having a face plate adapted to rearwardly sustain and advance a substantial amount of material to be treated, a plurality of spaced parallel vertically disposed transverse plates projecting forwardly from said shoe face plate substantial distances and providing auxiliary vibratory members and a plurality of material receiving pockets therebetween at the front of the face plate, said plates being extended transversely below said shoe, a vibrating means for said vibratory element comprising an unbalanced rotor mounted thereon, and vertically and horizontally adjustable means for supporting said vibratory element for vertical and horizontal adjustment relative to the material being treated and to said screed.

2. In a machine of the class described, the combination with a main carriage, of a reciprocating screed advanced with said main carriage, a vibratory element comprising an elongated flat shoe of substantial width disposed in advance of and in parallel relation to said screed and having a face plate adapted to rearwardly sustain and advance a substantial amount of material to be treated, a plurality of spaced parallel vertically disposed transverse plates projecting forwardly from said shoe face plate substantial distances and providing auxiliary vibratory members and a plurality of material receiving pockets therebetween at the front of the face plate, a vibrating means for said vibratory element, and vertically and horizontally adjustable means for supporting said vibratory element for vertical and horizontal adjustment relative to the material being treated and to said screed, said supporting means including a frame connected to the carriage and a flexible hanger supporting said element in depending relation to said carriage.

3. In a machine of the class described, the

combination with a main carriage, of a reciprocating screed advanced with said main carriage, a vibratory element comprising an elongated flat shoe of substantial width disposed in advance of and in parallel relation to said screed and having a face plate adapted to rearwardly sustain and advance a substantial amount of material to be treated, a vibrating means for said vibratory element, and vertically and horizontally adjustable means for supporting said vibratory element for vertical and horizontal adjustment relative to the material being treated and to said screed, said supporting means including a frame connected to the carriage and a flexible hanger connected to the frame and supporting said element in depending relation thereto.

4. In a machine of the class described, the combination with a main carriage, of a screed advanced with said main carriage, a vibratory element comprising an elongated flat shoe of substantial width disposed in advance of and in parallel relation to said screed and having a face plate adapted to rearwardly sustain and advance a substantial amount of material to be treated, a plurality of spaced parallel vertically disposed transverse plates projecting forwardly from said shoe face plate substantial distances and providing auxiliary vibratory members and a plurality of material receiving pockets therebetween at the front of the shoe and face plate, means for vibrating said vibratory element at high frequency, and means including flexible hanger means for the element for supporting said vibratory element for vertical adjustment relative to the material being treated, said supporting means being adjustable relative to said screed and carriage to position said element.

5. In a machine of the class described, the combination of a vibratory element comprising an elongated flat shoe of substantial width and having a face plate adapted to rearwardly sustain and advance a substantial amount of material to be treated, a plurality of spaced parallel vertically disposed transverse plates projecting forwardly from said face plate substantial distances and providing auxiliary vibratory members and a plurality of material receiving pockets therebetween at the front of the shoe and face plate, said vertically disposed plates being extended transversely below said shoe and being provided with enlargements of rounded section at the outer edges thereof, a vibratory means for said vibratory element comprising an unbalanced rotor mounted thereon, and vertically adjustable, translatable means for supporting said vibratory element for vertical adjustment relative to the material treated and for advancement in its adjusted positions.

6. In a machine of the class described, the combination of a vibratory element comprising an elongated flat shoe of substantial width and having a face plate adapted to rearwardly sustain and advance a substantial amount of material to be treated, a plurality of spaced parallel vertically disposed transverse plates projecting forwardly from said face plate substantial distances and providing auxiliary vibratory members and a plurality of material receiving pockets therebetween at the front of the shoe and face plate, said vertically disposed plates being extended transversely below said shoe, a vibratory means for said vibratory element comprising an unbalanced rotor mounted thereon, and flexible means for supporting said vibratory element relative to the material treated.

7. In a machine of the class described, the combination of a vibratory element comprising an elongated flat bottom shoe of substantial width and having a face plate adapted to rearwardly sustain and advance a substantial amount of material to be treated, a plurality of spaced parallel vertically disposed transverse plates projecting forwardly from said face plate substantial distances and providing auxiliary vibratory members and a plurality of material receiving pockets therebetween at the front of the shoe and face plate, a vibratory means for said vibratory element, and flexible means for supporting said vibratory element relative to the material treated.

8. In a machine of the class described, the combination of a vibratory element comprising an elongated flat shoe of substantial width and having a face plate adapted to rearwardly sustain and advance a substantial amount of material to be treated, a plurality of spaced parallel vertically disposed transverse plates projecting forwardly from said face plate substantial dis-

tances and providing auxiliary vibratory members and a plurality of material receiving pockets therebetween, said vertically disposed plates being extended transversely below said shoe and being provided with enlargements of rounded section at the outer edges thereof, and means for vibrating said vibratory element at high frequency.

9. In a machine of the class described, the combination of a vibratory element comprising an elongated flat shoe of substantial width and having a face plate adapted to rearwardly sustain and advance a substantial amount of material to be treated, a plurality of spaced parallel vertically disposed transverse plates projecting forwardly from said face plate substantial distances and providing auxiliary vibratory members and a plurality of material receiving pockets therebetween, said vertically disposed plates being extended transversely below said shoe, and means for vibrating said vibratory element at high frequency.

CORWILL JACKSON.
